UNITED STATES PATENT OFFICE

THOMAS A. KIRTON, OF JACKSONVILLE, FLORIDA

HIGHWAY MARKER

Application filed April 13, 1929. Serial No. 354,873.

This invention relates to means for painting markers on highways and street intersections and particularly to wheel supported devices carrying means for this purpose which 5 may be either pushed by hand or form part of or be drawn by an automobile.

The general object of this invention is to provide marking mechanism of this character in which the paint is forced out on to the 10 highway from a paint container by means of a series of atomizers operated by an air pump, thus causing a wide band of paint to be applied to the surface of the highway.

Other objects have to do with the mounting of the atomizers, the air pump, tanks, etc., and with the construction of the paint container or tank and other details of structure. I have illustrated my invention as applied to a hand operated or pushed marker but I do 20 not wish to be limited to this as the mechanism might be applied to an automobile or other power driven vehicle.

In the accompanying drawings:—

Figure 1 is a top plan view of a highway 25 marker constructed in accordance with my invention;

Figure 2 is a fragmentary sectional view of the clutch mechanism;

Figure 3 is a vertical sectional view 30 through the marker on the line 3—3 of Figure 1;

Figure 4 is a fragmentary elevation of one 35 of the traction wheels and the ratchet therefor;

Figure 5 is an elevation of the air pump used one side of the pump casing being removed;

Figure 6 is a fragmentary section of one of the atomizers.

Referring to these drawings, 10 designates 40 a frame or casing which may be of any suitable construction and which is designed to support a paint tank or tanks.

In the drawings I have shown two of these 45 tanks designated 11 and disposed on each side of a motor or engine 12. The frame is provided with the wheels 13 and the handle bar 14 extending out at one side of the frame so that the person operating the marker will 50 not walk in the track laid by the atomizers.

It will be understood that the frame or rather the track laid down by the atomizers is only as wide as the mark intended to be used and that the frame has a width only slightly greater than the mark intended to be applied 55 to the pavement.

The wheels 13 are driven from a shaft 15 as shown in Figure 4, the shaft carrying a pinion 16 meshing with the gear 17 on each traction wheel, each pinion 16 carrying with 60 in it ordinary ratchet mechanism consisting of the cam 18 and the balls 19. Inasmuch as this is an ordinary and common form of ratchet mechanism, it is not deemed necessary to describe it specifically. This permits the shaft 15 to rotate the traction wheels in the direction of the arrow in Figure 4 but the wheels are free to move reversely without being affected by the shaft 15, assuming that the engine is not running, when the machine is 65 pulled rearward.

Upon the forward movement of the wheels, the paint spraying mechanism becomes operative, but upon the rearward movement of the wheels, the paint spraying mechanism 70 becomes inoperative through this ratchet mechanism described and shown in Figure 4.

Disposed upon the frame are the two paint tanks 11 as previously stated. I have illustrated two tanks, but it will be understood 75 that the machine might be made with one tank, two tanks or more tanks as desired. Each tank is shown as being provided at its bottom with the pipe 20 extending downward into a transversely extending trough 21 and 80 each pipe 20 is provided with a valve 22. The pipe 20 extends nearly to the bottom of the trough 21 and the trough 21 is illustrated as extending nearly entirely across the machine, though it may be understood that a 85 plurality of troughs might be used.

Disposed in connection with the trough are a plurality of atomizers or nozzles 23 shown in detail in Figure 6, the lower end of each nozzle being contracted and discharging 90 transversely across the mouth or outlet of a pipe 24, this pipe 24 extending down into the trough 21 and opening adjacent the bottom thereof. The upper end of each atomizer 23 is connected by a pipe 25 to a supply pipe 26 95 100

which is shown as extending transversely across the machine. This pipe 26 is connected to an air pump, the casing of which is designated 27.

- 5 I may use any form of air pump which will be effective for the purpose, but I have shown a particular form of air pump having an eccentrically disposed rotor 28 and hinged blades 29. This pump specifically is 10 not my invention but is one found upon the market. The rotor is mounted upon the shaft 30. This air pump is connected to the air tank 31 which prevents fluctuations in air pressure and between the tank and air pump 15 proper, an outlet pipe 32 leads to the pipe 26. Opposite the pipe 32 a relief pipe 33 carries any suitable or ordinary form of relief valve 34 such as is commonly found in pumps of this character with weights 35 for regulating 20 the pressure. The pump is driven by means of the sprocket chain 36 operating over a sprocket wheel 37 carried upon the shaft 38. Mounted upon the shaft 38 is a sprocket wheel 39 connected by a sprocket chain 40 25 to a sprocket wheel 41 on the driving shaft of the motor or engine 12. The sprocket wheel 39 is loose upon this shaft 38 but is clutched to this shaft by any suitable clutch mechanism.
- 30 I have illustrated the sprocket wheel 39 as being shiftable longitudinally upon the shaft 38 and urged by a spring 43 against a friction clutch member 39^a pinned upon the shaft 38. The driving wheel 39 is shifted out 35 of engagement with the clutch member 39^a by means of the shipper rock shaft 42 shown in Figure 3 which is mounted in suitable bearings and carries at its upper end a handle 44 whereby it may be operated and adjacent its 40 lower end is provided with the usual fork 45 engaging a circumferential groove in the hub 46 on the sprocket wheel 39. Thus the operator can at any time throw off the power so as to stop the operation of the machine.
- 45 Mounted upon the rock shaft 42 is an arm 47 connected by a link 48 to an arm 49. This arm is mounted upon a sleeve which extends over the outside of a relief pipe and when the sleeve is raised, it raises the weights and 50 opens the relief valve. When the clutch is thrown out to throw the machine out of gear, the relief valve on the air pump is also opened to allow any air in the pump or any it might pump through the momentum of 55 the moving parts to escape and not pass through the atomizers. The action of putting the machine in gear will allow the relief valve to close and then the pump will force the air through the atomizers.
- 60 I have illustrated a machine having fifteen atomizers, but it will be understood that on some machines, a much less number of atomizers will be used as for instance some machines will have only nine atomizers and this 65 relief valve will permit the escape of any

air that cannot be forced through the number of atomizers used. It will be seen that this machine is guided by the operator but propelled by the engine or motor 12 which also operates the air pump, this being secured 70 by mounting upon the shaft 15 the sprocket wheel 50 which receives power through the chain 51 from the sprocket wheel 52 on the shaft 38 which in turn as previously described, is driven from the engine. Of 75 course, with the construction illustrated in Figure 4, the power will be used to drive the traction wheels forward, but the machine may be drawn rearward while the motor is operating by disengaging the clutch 39^a. If 80 the machine is used as a trailer, the sprocket chain 51 may be removed so that the motor will have no effect upon the traction wheels, but will only drive the air pump.

While I have illustrated certain details of 85 construction and arrangements of parts, it will be understood that many variations might be made in the details of construction without departing from the spirit of the invention as defined in the appended claims. 90

The atomizers are to be placed sufficiently close together so that the paint will be discharged downward on to the surface of the street to form a band or bands of approximately the width desired so long as the machine is moving forward. When the clutch is thrown out in order to stop the machine, the air pump will stop and the relief valve will be immediately opened.

In many cases, it is desirable that the paint 100 discharged upon the street shall be parti-colored, as for instance bands of red, white and blue for national highways. Under these circumstances, of course, several tanks will be used for the different colored paints and a separate trough will be provided for each tank with atomizers discharging therefrom. Of course, it will be understood that the atomizers may be disposed any desired distance 105 from the roadway which will cause the paint 110 to spray properly upon the roadway.

It will be seen that the mechanism as described is very simple and easily operated. By this means, the usual markers down the middle of the highway may be readily and economically painted and the parking lines, pedestrian markers and other indicating marks of like character may be readily applied, particularly to concrete streets. 115 Where the machine is self-propelled, the operator can ride and paint many miles of roadway in a day.

It will be seen that as soon as the machine is driven forward, air will be forced through 120 the atomizers and paint is applied to the surface, but that when the machine is forced backward, no air is forced through the atomizers and the machine does not paint. There is no leakage of paint when the ma- 125

chine is standing idle or when the clutch is thrown out.

It will be understood that the trough 21 constitutes in effect a supplementary tank and that the pipes 20 constantly retain a predetermined level of liquid in this tank or trough 21 just sufficient to keep the mouth of a pipe 20 covered. If the level of liquid should sink so low as to uncover the mouth of the pipe, the paint will pass from the main tank into the trough or supplementary tank 21.

While I do not wish to be limited to any particular arrangement of the atomizers, except that they shall be close enough together that a solid band or bands or in other words, multiple bands may be painted upon the pavement, yet preferably the atomizers will be arranged about three-eighths of an inch 20 from each other so as to form a band or a multiple of bands approximately eight or nine inches wide. If a plurality of bands are to be painted, the atomizers are placed in batteries of three atomizers, three-eighths of 25 an inch apart with a blank space of about one inch separating the batteries. This arrangement will paint a narrow strip, leave a strip of roadway unpainted and then paint another narrow strip or more.

20 The construction which I have illustrated is motor driven or hand guided and the pawl and ratchet shown in Figure 4 is so arranged that the shaft 15, when turned forward by the engine will drive the machine forward. 35 Yet the machine may be rolled forward in gear. To move the machine backward, it is only necessary to throw out the clutch and then when the machine is drawn backward, the pinions make the shaft revolve, but as 40 the machine is out of gear this is not difficult. Where a paint atomizer is used constructed in accordance with my invention, but propelled entirely by man power, the pawl and ratchet are so arranged, as in the ordinary 45 mowing machine, that when the machine is pushed forward, the shaft 15 will operate the air pump, the power being taken from the traction wheels of the machine, but when the machine is drawn backward, the air pump 50 will not be operated. Such a machine may be drawn from place to place without operating the air pump. The air pump is operated when the machine is pushed.

In the construction shown in the instant 55 drawings, the pawl and ratchet shown in Figure 4 is reverse from that of an ordinary hand lawn mower and operates when the clutch is in and stops when the clutch is thrown out. When it is not desired to paint 60 the pavement, the model is pushed with the clutch out but without power being transmitted from the engine. It is to be understood, of course, that on the markers which are self-propelled and where the operator 65 walks to guide the machine, that is, the con-

struction which is illustrated in my drawings, it will be necessary that the operator in moving from one place to another and where it is not desired to paint between certain points, to first throw out the clutch and then as soon as the machine has stopped, the operator will raise the relief valve cap, manually, and this relief valve will be held open.

Then he puts the machine in gear and the machine will propel itself to the next point to be painted with all air escaping through the valve and none going through the atomizers. When the surface to be painted is reached, the operator stops the machine and releases the mechanism holding the relief valve open and the sliding sleeve over the relief valve pipe will open and close this valve as the clutch is thrown in and out, the engine remaining running all the time.

It will be understood that with this machine using tanks of different colored paint, that two stripes may be painted, each two inches wide, separated from each other by a width of four inches or with a different arrangement of the atomizers, a three inch stripe may be painted in the middle and two one inch stripes on each side separated from the middle stripe and that by having two or more tanks, these stripes may be painted in different colors and these stripes may be either separated from each other or extend side by side.

I claim:—

1. A highway marker of the character described, comprising a wheeled frame, a normally air-tight paint tank mounted thereon and having a downwardly extending valved discharge pipe, a supplementary tank disposed below the first named tank and into which the pipe discharges whereby to maintain a constant level of paint in the lower end of the supplementary tank slightly above the mouth of the valved pipe, a plurality of paint discharge nozzles communicating with the supplementary tank adjacent the bottom thereof and atomizer nozzles discharging past the ends of said discharge nozzles and on to the roadway, an air pump, means connecting the air pump to the atomizing nozzles, and means for operating the air pump.

2. A highway marker of the character described comprising a wheel supported frame, a paint tank mounted thereon, a supplementary tank mounted thereon and communicatively connected to the paint tank, means for maintaining a constant level of paint in the lower end of the supplementary tank, a plurality of discharge nozzles communicatively connected to the lower end of the supplementary tank and receiving paint therefrom and atomizer nozzles discharging downward across the open ends of the paint discharge nozzles, and an air pump connected to said atomizer nozzles.

3. A highway marker comprising a supporting frame, a paint tank mounted thereon,

- a supplementary tank mounted thereon having a length approximately equal to the width of the marking band to be painted on the highway, means for maintaining a constant 5 level of liquid in the lower end of the supplementary tank, a plurality of discharge nozzle mounted upon the lower end of the supplementary tank at spaced distances from each other, each discharge nozzle extending 10 into the bottom of the supplementary tank and a downwardly discharging air nozzle exterior to the supplementary tank, and means for forcing air into said nozzles.
4. A highway marker including a wheel 15 supported frame, traction wheels therefor, a paint tank mounted upon the frame, a supplementary tank into which the paint tank discharges, means for maintaining a constant level of liquid in the lower end of the 20 supplementary tank, a series of discharge nozzles mounted upon the supplementary tank, and communicatively connected to the interior thereof to receive paint therefrom, each discharge nozzle having associated with it an 25 air nozzle discharging downward on to the highway, an air pump mounted on the frame and operatively connected to the atomizing nozzles and having a relief valve, a motor for driving the air pump, and manually controlled means for operatively disconnecting the motor from the air pump and simultaneously opening said relief valve or vice versa.
5. A highway marker including a supporting frame, a paint tank mounted thereon, a 35 plurality of discharge nozzles receiving paint from the paint tank, atomizer nozzles discharging across the discharge nozzles, the discharge nozzles and atomizer nozzles being disposed in such relation that paint discharged 40 thereby upon the highway will form a solid band, an air pump, means connecting the air pump to the atomizer nozzles, means for operating the air pump, and means for disconnecting the air pump from its operating 45 means and simultaneously discharging the air from the pump directly into the atmosphere.
6. A highway marker of the character described, comprising a supporting frame, traction wheels therefor, a paint tank mounted 50 thereon, a trough extending transversely of the frame, means conducting paint from the paint tank to said trough and maintaining a constant level of paint within the trough, a plurality of discharge nozzles disposed at intervals along the trough, each nozzle at one end dipping into the paint and at its other end extending horizontally outward above the top of the trough, vertically disposed 55 atomizer nozzles associated one with each discharge nozzle and discharging downward on to the roadway, the discharge nozzles being disposed in such proximity that the paint discharged therefrom will form a solid band 60 on the roadway, means connecting the air pump to the atomizing nozzles, a motor for 65

driving the pump and traction wheels, manually control means for disconnecting the motor from the air pump and the traction wheels and simultaneously discharging the air from the air pump to the atmosphere.

7. A highway marking mechanism of the character described, including a paint tank, a trough disposed below the paint tank, a pipe leading from the paint tank and terminating short of the bottom of the trough but below the top of the trough and constituting a barometric feed maintaining a level of paint within the trough slightly above the mouth of the pipe, and atomizing nozzles sucking paint from the trough and discharging it on to the roadway.

In testimony whereof I hereunto affix my signature.

THOMAS A. KIRTON.
